UNITED STATES PATENT OFFICE.

MARY STARMER, OF NEWPORT NEWS, VIRGINIA.

SUSPENDER CONNECTION.

1,383,164.

Specification of Letters Patent. Patented June 28, 1921.

Application filed August 5, 1920. Serial No. 401,328.

To all whom it may concern:

Be it known that I, MARY STARMER, a citizen of the United States, residing at Newport News, in the county of Warwick and 5 State of Virginia, have invented certain new and useful Improvements in Suspender Connections, of which the following is a specification.

My present invention relates to improvements in suspender connections, which may be utilized in conjunction with men's suspenders or women's garment supporters.

The primary object of the invention is the provision of a flexible and adjustable connection of this type, which is capable of freedom in movement to adapt itself to different positions assumed by the wearer, and which provides a comfortable and efficient means for performing its required functions.

To this end the invention consists in certain novel combinations and arrangements of parts involving a two piece guard-buckle or connection for the suspender strap and 25 button-hole tabs or suspending tabs as will be hereinafter more specifically set forth and claimed.

While hereinafter referring to the invention as a suspender connection for men's wear, it will readily be apparent that the 30 subject matter of the invention may be embodied in various ways for affording an efficient, simple, and durable part of a garment supporting or suspending device.

In the accompanying drawings I have 35 illustrated one complete example of the physical embodiment of my invention, wherein the parts are combined and arranged according to the best mode I have so far devised for the practical application of the principles of my invention.

Figure 1 is a view in elevation showing a portion of the shoulder strap of a pair of suspenders with my guard-buckle suspending the button-hole strap therefrom.

Fig. 2 is a rear view showing the guard-buckle and a portion of the button-hole tabs, the shoulder strap being shown in dotted lines.

50 Fig. 3 is a view in perspective depicting the buckle portion of the device and a fragment of the button-hole tabs suspended from the buckle hooks.

Fig. 4 is a vertical, sectional view on the 55 broken line 4—4 of Fig. 1.

Fig. 5 is a rear perspective view of the buckle guard.

Fig. 6 is a fragmentary perspective view showing the method of connecting the button-hole tabs to the buckle hooks.

In the illustrated form of my invention as shown in the drawings 1 designates a shoulder strap of flat web preferably of inelastic material or fabric which is doubled back or folded upon itself to form a loop 2. The 65 shoulder strap may or may not be provided with a usual adjusting device, not shown, for varying the length of the strap.

The two button-holes tabs 3, 3 are spaced apart, and each is provided with a perforation 4 near its upper end. The strap and tabs may be suitably reinforced to render them durable and able to withstand wear, due to ordinary use of the device.

The buckle guard as a whole is indicated 75 by the numeral 5 in Fig. 5, and is fashioned in inverted U-shape as disclosed in the drawings. The front plate 6, which is smooth metal member may be ornamented as desired, and the back plate 7 is stamped 80 or cut out to form an inwardly bent panel 8. The formation of the panel provides a longitudinal slot 9 near the lower edge of the back plate, and also provides a bar 9' extending substantially the length of the plate. 85

In Fig. 4 it will be seen that the loop 2 of the shoulder strap is passed around the bar 9' and through the slot 9, and by this means the guard 5 is secured to the shoulder strap. The end bars of the back plate 7 retain the loop 2 in position, and the material of the loop neatly fits about the bar 9' as shown. A shorter longitudinally extending slot 10 is provided in the metal of the panel 8 for the accommodation of the 95 buckle.

As shown in Fig. 3 the suspending buckle is fashioned of a single piece of wire of proper dimensions and suitable gage and this buckle is partially inclosed within the 100 guard 5. At its extremities the buckle is formed with downwardly bent U-shaped end hooks 12, 12 over which the perforated ends 4 of the button-hole tabs 3 are suspended. Centrally of the buckle are provided a pair 105 of double bends 13, 13 forming an upper retaining arm and a lower retaining arm, and the material or wire of the buckle is offset at 14 in the joint between the buckle and these retaining arms.

In Figs. 2 and 4 it will be apparent that the offset portion 14 is located in the slot 10 of the back plate 7, and that the retaining arms or prongs 13 are outside the guard 5 and project above and below the slot 10.

The major portion of the buckle with the perforated ends 4 of the button-hole tabs are inclosed within the inverted U-shape guard 5. Because of the suspending connection of the tabs on their hooks within the guard the tabs are securely attached on their hooks, and are not likely to become accidentally displaced. The arrangement of the buckle with its arms 13 exterior of the slotted back plate 8 permits the required freedom of movement of the tabs with relation to the guard, and by this means a comfortable and flexible suspender connection is provided.

20 The device is simple in construction, involving as it does a two piece connecting device, and the strap and tabs are attached to the suspender connection in a simple, but proficient manner.

25 Having thus fully described my invention what I claim as new and desire to secure by Letters Patent is:

1. In a suspender connection the combination with an inverted U-shape guard hav-

ing a panel formed with a slot, and forming 30 an attaching bar, of a shoulder strap attached to said bar, a buckle retained within said guard, and hooks on said buckle, and perforated button-hole tabs suspended from said hooks within the guard.

35 2. A suspender connection including an inverted U-shape guard and shoulder strap attached thereto, said guard having a slot in its rear plate, a buckle within said guard, and perforated button-hole tabs suspended 40 from said buckle and integral retaining arms on said buckle exterior of the slotted back plate, for the purpose described.

3. The combination in a suspender connection with a looped shoulder strap, of an 45 inverted U-shape guard having a slotted panel stamped from its rear plate and an attaching bar for said shoulder strap, a buckle inclosed within said guard having downwardly bent U-shaped end hooks, perforated button-hole tabs suspended on said hooks, said buckle having an offset portion 50 extending outwardly through a slot in the panel, and upwardly and downwardly extending integral arms on said buckle exterior of the slotted panel.

MARY STARMER.
